UNITED STATES PATENT OFFICE.

ERNEST STUART DANIELS, OF WASHINGTON, DISTRICT OF COLUMBIA.

BUILDING JOIST AND BEAM COUPLING.

Application filed December 15, 1924. Serial No. 755,961.

This invention relates to building construction and more particularly to coupling or joinery means for wall-posts, beams, joists and other parts of the elementary or skeleton structure of a house, garage, shed or the like.

The principal object is to provide simple and efficient means of the character referred to, by which the structural timbers of parts of a building may be expediently and economically assembled and fixed rigidly in place without necessity for mortising or the use of nails, thus facilitating the work of construction with great saving in time, labor and material, especially in the erection of "ready-made" or "ready-cut" buildings or structures, to which the invention is particularly applicable.

Practicability and inexpensiveness in cost of manufacture are further desiderata which have been borne in mind in the production of my improved structure joining or coupling means.

The invention will be first hereinafter more particularly described with reference to the accompanying drawings which are to be taken as a part of this specification and then pointed out in the claims at the end of the description.

In said drawings, Fig. 1 is a partial perspective view of an incomplete building erected in accordance with my invention, illustrating the manner in which sheathing and frame structural parts are assembled and joined together in place.

Fig. 2 is a perspective view of the "joiner" or coupling elements embodying this invention, the associated uniting parts of a frame structure being shown fragmentarily.

Fig. 3 is a partial perspective view of vertical and superposed horizontal parts of a frame structure adapted to be joined or secured together by my improved coupling means.

Fig. 4 is a detached perspective view of a slightly modified form of coupling element.

Fig. 5 is a perspective view illustrating the novel manner in which composite panels or sections of sheathing are secured in place between parallel wall posts, the latter being shown fragmentarily.

The remaining figures are merely illustrative of various uses to which my improved "joiner" or coupling elements may be put either with or without slight modification in assembling and securing the structural

parts of a building frame or scaffold together in their different relations with respect to each other; Fig. 6 being a perspective fragmentary view of meeting beams supportingly secured at an angle to each other forming a corner; Fig. 7 a fragmentary perspective view of uniting extended sections of a horizontal beam; Fig. 8 a fragmentary perspective view of uniting tie-beam and strut, showing a desirable modification for such purpose in the form of one of the coupling members; Fig. 9 a fragmentary perspective view of uniting mortised sections of a vertical joist or truss; and Fig. 10 a fragmentary perspective view of uniting mortised sections of an inclined brace or strut member.

Referring to the drawings in which like reference numerals are used to indicate corresponding parts throughout the several views, 11, 12, 13 and 14 respectively denote the usual sill, upright wall-posts, tie-beam and head-beams of a building or structure, while 15, 16, 17 and 18 respectively designate the king-post, ridge-beam, rafters and inclined braces or struts thereof.

Said beams, or frame structural parts of the building with the exception of the rafters, are unitingly assembled and rigidly secured in their respective places as illustrated in Fig. 1, by means of my improved joiner or coupling elements hereinafter described, said rafters as shown, being preferably supported in place by means of angular brackets 19 and 20, of the character shown and described in my copending application Serial Number 754,303 filed December 6, 1924, for improvements in joist and rafter suspension brackets.

The joiner or coupling elements embodying this invention comprise metallic plate members 21 and 22 adapted to complementary interlocking engagement with each other, the first named plate being cast with intersecting ribs or formed substantially in the shape of a cross as shown, the second named plate being correspondingly recessed or grooved to a depth conforming therewith, so as to accommodate or complementary receive the former as illustrated clearly in Figs. 2 and 3. Registering transverse holes 21^a and 22^a are provided respectively in the ends of the plates 21 and 22, through which ordinary cotter-keys or pins are passed to interengagingly secure the two plates together.

Said interlocking plate members are secured in opposition to each other upon junctural ends or surfaces of the several beams or structural parts of a building, by ordinary flat-headed screws extended through apertures provided therein for such purpose as shown, such plates in predetermined engaging or interlocking relation to each other, being thus secured on the ends and at proper points along the surfaces of the respective frame members of a structure, at which they are predesigned to be fixed or united with one another, thereby permitting the several parts of the structure to be easily, quickly and rigidly assembled together.

Referring to Fig. 4 in which a slight modification in form of the plate 21 is illustrated, the cross-bar extremities thereof, may if desired, be recessed as at 21^b, to correspond or register with longitudinal grooves provided in the wall-posts 12 for a purpose hereinafter defined.

Referring now to Fig. 5, illustrating the novel method by which sheathing material may be conveniently and expediently applied, longitudinal grooves 12^a are for such purpose provided in opposite sides of the upright wall-posts 12 which thus form parallel guide-ways accommodating the oppositely extended splines or tongues of sheathing panels 23, the latter being formed in composite sections of the character shown and described in a joint patent to myself and Harold P. Schuck, for improvements in parquet flooring and wall paneling, No. 1,510,924 dated October 7, 1924, having fixed end splines 23^a and loose assembly splines 23^b and 23^c respectively for the grooved ends and sides thereof, said panels being thus interlockingly fitted in place by sealing tongue and groove connections one upon the other between adjacent wall-posts, as shown in Fig. 1.

Referring to Fig. 8 in which an inclined brace is shown connecting with a horizontal beam, the plate 22 may be formed or provided with an extremal upright flange or heel portion 22^b against which the inclined brace may press and relieve the angular pressure or strain otherwise imposed upon the plate members.

When mortised sections of vertical or inclined posts or trusses are interlockingly joined together as illustrated in Figs. 9 and 10, a girding or encircling safety-brace 24 may be advantageously employed as shown, to reinforce the union therebetween.

It is thought that the novelty and utility of my improved joiner or coupling means will be obvious from the foregoing description and the distinctive features and economic advantages incident to the simple mode of building construction set forth herein, will be readily appreciated.

Since the coupling plate elements may be

applied to various uses, and modifications other than those herein set forth, may be made without departing from the spirit and scope of my invention, I do not desire to be limited by the appended claims to the specific form, construction and arrangement hereinbefore illustrated and described.

Having thus described my invention, what I claim as new and desire to secure by Letters Patent of the United States is:

1. In combination with the structural frame members of a building, means for assembling and joining said members together at their points of juncture with each other, said means comprising solid interlocking complementary tongue and groove plate elements secured in opposition to each other upon and between meeting surfaces or ends of the respective frame parts.

2. In combination with the structural frame members of a building, means for coupling said members together at desired points; said means comprising complementary interlocking crossed tongue and groove plate elements interposed and secured in opposition to each other between the ends or surfaces of the respective frame members at their points of juncture with each other.

3. Means for assembling and joining the structural frame members of a building together, said means comprising complementary tongued and grooved solid flat plates secured in opposed interengaging relation to each other upon and between the junctural ends or surfaces of the respective frame members.

4. Means for joining and securing the frame structural parts of a building together, said means comprising complementary plate elements securable in opposed relation upon junctural surfaces of the respective frame parts and adapted to interlocking engagement with each other, one of said plates being formed with a tongue substantially in the shape of a cross and the other of said plates being correspondingly recessed so as to receive and retain the former.

5. Means for joining and securing the structural frame parts of a building together, said means comprising complementary plate elements securable in opposed relation upon junctural ends or surfaces of said parts and adapted to interlocking engagement with each other, one of said plates being formed with a tongue substantially in the shape of a cross, the other of said plates being correspondingly recessed to receive the former and means for locking said plates together.

6. In combination with a building, means for joining and securing the structural frame members thereof together in proper supporting relation each to the other, said means comprising complementary interlocking tongue and groove plate elements se-

curable in opposition to each other upon and between the ends or surfaces of the respective members at their points of juncture or unity with each other.

5 7. In combination with a building frame structure, means for joining and securing the structural members thereof together in proper supporting relation each to the other, said means comprising complementary inter-

locking plate cross-shaped tongue and groove 10 elements securable in opposition to each other upon and between the ends or surfaces of the respective members at their points of juncture or unity with each other and means for inseparably locking said plate elements 15 together.

In testimony whereof I affix my signature.

ERNEST STUART DANIELS.
